UNITED STATES PATENT OFFICE.

JOSEPH ABRAMOWITZ, OF MADISON, ILLINOIS, ASSIGNOR OF ONE-HALF TO JOHN J. SELB, OF VENICE, ILLINOIS.

ARCH SUPPORT.

Application filed June 23, 1924. Serial No. 721,878.

This invention relates to a certain new and useful improvement in arch-supports and has for its chief object the provision of a simple, inexpensive arch-support which may be readily fitted in the shoe and which is capable of convenient height adjustment to build up a shoe or other footwear to properly and comfortably support the metatarsus or instep of the foot.

With the above and other objects in view, my present invention resides in the novel features of form, construction, arrangement, and combination of parts hereinafter described and pointed out in the claims.

In the accompanying drawing,

Figure 1 is an inner marginal edge view of an arch-support embodying my invention;

Figure 2 is a longitudinal sectional view of the arch-support;

Figure 3 is a transverse sectional view of the arch-support;

Figure 4 is a fragmental inverted plan view of the same;

Figure 5 is an inner marginal edge view, partly broken away and in section, of a modified form of arch-support embodying my invention; and

Figure 6 is a transverse sectional view of the modified arch-support of Figure 5.

Referring now more in detail and by reference characters to the said drawing, which illustrates a preferred embodiment of my invention, A designates the support proper, which includes a lower member or base 2 formed or constructed of suitable material and shaped and contoured to conveniently fit within a shoe at the shank and heel thereof.

1 indicates the upper member of the support A, which is of a size and contour to likewise conveniently fit within the shoe, and which not only normally inclines transversely, that is to say, is higher relatively to base 2 at its inner margin than at its outer margin, but is also bodily both longitudinally and laterally permanently shaped to approximately conform to and provide a support for the arch of the human foot.

The base 2 and upper member 1 may be formed from a single section of suitable leather, fiber, or the like, with one edge of their margins integrally joined or connected; but such parts of the support are preferably of separate sections of suitable material

preferably stitched or otherwise fastened operatively together at their one or outer side margin, as at 3, Figure 4. As so formed and constructed, the base 2 and upper member 1 are yielding or movable relatively to each other somewhat in the nature of the pivotally connected members of a hinge, and as also so constructed and finished support proper A may be used and employed within the shoe to proportionately with the combined thickness of its members 2 and 1 build up the arch of the shoe.

However, to further and adjustably build up the arch of the shoe to meet the requirements of different feet, I employ as a part of the support proper a height-adjusting member B that likewise in the preferred form of the arch-support, as illustrated in Figures 1, 2, 3, and 4, includes a pair of companion sections 4 and 5 of leather or other suitable material superimposed for co-operation one upon the other and either integrally or otherwise, as, for instance by stitching, united or permanently connected together along their one or outer marginal edge for relatively hinged or swinging movement. As best seen in Figures 1, 2 and 3, the sections 4 and 5 have inner faces adapted for registration when the sections are in abutting relation. The sections 4 and 5 also have their greatest thickness at approximately the longitudinal center of their free inner marginal edge, from which point both sections 4 and 5 by skiving or otherwise are both longitudinally to their opposite end margins and transversely to their said outer marginal edge reduced to relatively little thickness.

Permanently seated in alignment in the sections 4 and 5 of member B at approximately their point of greatest thickness, is a pair of threaded sockets 6, 6, fitting in which for threaded co-operation is a pair of oppositely threaded screw-members 7, 7, oppositely projecting from, and at preferably the axial center of, a preferably knurled or otherwise peripherally roughened disk 8 disposed for finger actuation at the free inner marginal edge of the member B, the disk 8 being disposed for rotary movement for the most part in a pocket or recess 9 provided conjointly for the purpose upon the inner matching faces of the sections 4 and 5. It will be evident that, as the disk 8 is rotarily actuated in one or the other direc-

100

105

110

tion, the sections 4 and 5 will correspondingly be hingedly spread apart or brought together, the sections 4 and 5 being normally in approximately flatwise abutting relation 5 at their inner faces.

The member B is of such size relatively to the support proper A as to endwise fit between its members 1 and 2, as seen in Figures 1, 2, and 3, and efficiently functions, as 10 the disk 8 is adjustably actuated in its seat, to selectively transversely or hingedly space or spread the sections 4 and 5 and correspondingly members 1 and 2 of the support A to further build up the shoe at its arch 15 to adjustably meet the requirements of different feet.

The base-member 2 of the support-proper A is provided longitudinally adjacent its free inner edge with a series of spaced perforations 10, adapted selectively for removable engagement with which is a pin or stud 11 depending from the under-member 5 of member B. By means of said co-operating pin 11 and perforations 10, the member B, being adapted also for selective location longitudinally between the members 1 and 2 25 of support A, may be removably secured against displacement in any selected location intermediate the members 1 and 2 of support A.

Frequently the member B, due to the combined dimensions of its members or sections 4 and 5, even when said sections are in normal, approximately flatwise abutting relation 35 at their inner faces, too greatly hingedly spreads or spaces the members 1 and 2 of the support proper A. In such instances, I dispense with the lower member or section 5 of the member B and, by clinching, riveting, 40 or the like, provide the lower member 2 of the support A upon its upper face and longitudinally at its inner margin with a suitably elongated plate or strip 12 formed lengthwise with a series of tapped threaded 45 apertures 13 registering with the perforations 10 of the member A, as best seen in Figure 5. The apertures 13, in turn, provide seats for the under screw-member 7' of the disk 8', by means of which the height-adjusting member or section 4' may be selectively located lengthwise of the support A. It will be evident that upon actuation 50 of the disk 8', the member or section 4' and correspondingly the upper support member 1' will be elevated or lowered relatively to the lower support member 2' to meet the requirements of different users.

My new arch-support may be inexpensively manufactured, may be made in various shapes and sizes to fit shoes of different sizes and to accommodate arches or insteps of various contour, and is exceedingly effective in the performance of its intended functions.

I am aware that minor changes in the

form, construction, arrangement, and combination of the several parts of the arch-support may be made and substituted for those herein shown and described without departing from the nature and principle of my invention.

Having thus described my invention, what I claim and desire to secure by Letters Patent is:

1. In an arch support adapted to fit within 75 a shoe, a pair of co-operating relatively movable superimposed sections, in combination with means adapted for removable edgewise disposition intermediate said sections and including a pair of relatively movable members and a screw-member having oppositely threaded opposed portions having engagement with said members, respectively, for adjustably spacing said members for correspondingly spacing said sections for varying the arch supporting height of the support.

2. In an arch support adapted to fit within 90 a shoe, a pair of co-operating superimposed sections having connection at one side margin for relatively hinged movement, in combination with means adapted for removable edgewise disposition intermediate said sections, and including a pair of relatively movable members each having a threaded 95 recess, and a screw-member having oppositely threaded opposed portions having engagement with said members, respectively, at said recesses for adjustably spacing said members for correspondingly hingedly spacing said sections for varying the arch supporting height of the support.

3. In an arch support adapted to fit within 105 a shoe, a pair of co-operating superimposed sections having connection at one side margin for relatively hinged movement, in combination with means adapted for removable edgewise disposition intermediate said sections for hingedly spacing said sections for varying the arch supporting height of 110 the support, said means including a pair of members having connection at one side margin for relatively hinged movement, said sections having inner faces adapted for registration when the sections are in abutting 115 relation, and each section having a threaded recess opening upon its said inner face, a screw-member comprising oppositely threaded opposed portions transversely disposed to, and engaging at said recesses with, said members for hingedly spacing the same, and a disc fixed to the screw-member intermediate 120 its threaded portions and disposed for rotary moment intermediate the sections for actuating the screw-member.

4. In an arch support, a pair of connected 125 relatively hingedly movable members having opposed threaded recesses, and a screw-member having oppositely threaded opposed portions disposed at a right angle to said mem-

bers and having engagement with said members at said recesses, respectively, for spacing said members the one from the other.

5. In an arch support adapted to fit with-
in a shoe, height adjusting means includ-
ing a pair of members having connection at
one side margin for relatively hinged move-
ment and having their greatest thickness
10 along their opposite side margin, said sec-
tions having inner faces adapted for regis-
tration when in abutting relation and each
section having a threaded recess opening
15 upon its said inner face, and a screw-member
having oppositely threaded opposed por-
tions transversely disposed to, and having engage-
ment at said recesses with said members for
members for hingedly spacing the same the one
from the other.

6. In an arch support adapted to fit with-
20 in a shoe, height-adjusting means including
a pair of members having connection at one

side margin for relatively hinged movement
and having their greatest thickness along
their opposite side margin, said sections hav-
ing inner faces adapted for registration 25
when in abutting relation, said sections being
of gradually reduced thickness longitudi-
nally towards their longitudinal edges and
transversely toward their first-named mar-
gin, and each having a threaded recess open-
30 ing upon its said inner face, a screw-member
having oppositely threaded opposed portions
transversely disposed to, and having engage-
ment at said recesses with said members for
hingedly spacing the same the one from the 35
other, and a disc fixed to the screw-member
intermediate its threaded portions and dis-
posed for rotary movement intermediate the
sections for actuating the screw-member.

In testimony whereof, I have signed my 40
name to this specification.

JOSEPH ABRAMOWITZ.
